METHOD AND MEANS FOR MAKING SLIDERS
FOR SLIDE FASTENERS

Maurice Voity, Long Island City, and George A. Griffiths, Kew Gardens, N. Y., assignors to Universal Slide Fastener Co. Inc., Long Island City, N. Y., a corporation of New York

Application June 6, 1942, Serial No. 446,062

13 Claims. (Cl. 90—18)

This invention relates to a method and means for making sliders for slide fasteners. More particularly, the invention is concerned with the provision of an improved method and apparatus for reducing the height of the rails of slider wing blanks which are integrally connected in a long strip.

One of the objects of our invention is to provide an improved apparatus of the character described which is capable of operating at a high speed and in a continuous and accurate manner upon a strip consisting of integrally connected slider wing blanks in order to reduce the height of the slider rails to a predetermined elevation.

Another object of our invention is to provide an improved apparatus of the character described in which the slider rail height reducing means is operated from a source of power which simultaneously causes the strip of slider wing blanks to be moved relative to said rail height reducing means.

A further object of our invention is to provide an apparatus and method of the character described through whose use the height of the slider rails is reduced in such manner as to leave the trimmed edge smooth and thus dispense with further finishing steps.

An additional object of our invention is to provide an apparatus of the character described which shall comprise relatively few and simple parts, and which shall be adjustable for use with slider wing blanks of various sizes, which shall be rugged in construction and efficient in operation to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

Certain features of the apparatus and method herein shown or described but not claimed are shown, described and claimed in our copending application Serial No. 426,694, for Method and means for making sliders for slide fasteners, filed January 14, 1942, of which this application is a continuation-in-part.

In the accompanying drawings, in which is shown one of the various possible embodiments of this invention and wherein like numbers refer to like parts;

Fig. 1 is an end elevational view of an apparatus embodying our invention;

Fig. 2 is a front elevational view thereof with portions broken away to clearly show the means for feeding the strip of integrally connected slider wing blanks;

5 Fig. 3 is an enlarged sectional view taken substantially along the line 3—3 of Fig. 2, showing the guides for directing the path of the strip through the apparatus;

Fig. 4 is a sectional view taken substantially 10 along the line 4—4 of Fig. 3;

Fig. 5 is an enlarged sectional view taken substantially along the line 5—5 of Fig. 3; and

Fig. 6 is an enlarged sectional view taken substantially along the line 6—6 of Fig. 4.

15 Referring now to the drawings, we have there shown an apparatus 10 which embodies our invention and is specially designed and constructed to reduce the height of the rails of slider wing blanks which are integrally connected in a long 20 continuous strip S, such as is shown and described in the said copending application.

This strip S comprises a series of integrally connected slider wing blanks 12 (Fig. 3) having rails 14 which are higher than required in the 25 finished slider. Each rail consists of a portion 16 parallel to the longitudinal axis of the strip and an outwardly diverging contiguous portion 18. Successive wing blanks are oppositely oriented and are connected to each other, where 30 the parallel rail portions 16 are adjacently disposed, by a link 20 substantially coplanar with the wing blank 12. Said wing blanks are connected to each other adjacent the diverging rail portions 18 by a diamond-shaped link 22 raised 35 above the plane of the wing blanks 12 and the top of the rails 14. The width of the raised diamond-shaped link 22 is less than the distance between the inside surfaces of the parallel rail portions 16, and said raised link is disposed substantially medially of said rail portions.

40 The apparatus 10 for reducing the oversized slider rails to their proper height comprises revolving material removing means M, a gauge G for guiding the strip S into proper position relative to the material removing means, a device F for feeding said strip to and beyond the material removing means, a common source of power P for actuating the material removing means and feeding device, and suitable means H for holding these parts in proper position to function as a unitary organization for trimming the rails.

45 The means H for commonly supporting and holding the several parts of the apparatus 10 in their proper positions comprises a bed plate 24 carried by a pedestal 26. As will be apparent 50

during the course of the following description, said supporting means also includes the casings and bases of the various machine parts which are secured directly or indirectly to the bed plate, as well as standards, brackets and the like, similarly attached to the bed plate and adapted to serve as auxiliary supporting means.

The common source of power P comprises an electric motor 28 mounted on a bracket 30 secured to the pedestal 26. Through pulley 35, belt 36 and pulley 38, said motor 28 operates at high speed a drive shaft 32 which is journaled in a bearing box 40 bolted to the bed plate 24.

The arbor end 34 of said drive shaft 32 extends beyond the bearing box 40 and is threaded to receive revolving material removing means M which may comprise a pair of fluted cutting disks 42 and 42' spaced apart a distance less than the distance between the interior surfaces of the parallel rail portions 16. The width and disposition of the disks is such that when the strip S is moved transversely of the arbor 34 each cutter will be in proper location to trim parallel rail portions 16 and diverging rail portions 18 disposed along one longitudinal edge of the strip. In order to dispose the cutters in this fashion, a flange 44 is fixed to the arbor 34 adjacent the bearing box 40. Spacing collars 46 and 48 shiftable on the arbor fix the distance between the innermost cutter 42 and the flange 44, and an intermediate spacing collar 50 fixes the distance between the two cutting disks 42, 42'. After the disks 42, 42' and collars 46, 48 and 50 have been slipped on the arbor 34, they are clamped in position by a nut 52. The cutting disks may be internally grooved to cooperate with a key (not shown) on the arbor 34 so as to prevent rotation of said disks relative to the arbor.

The gauge G for guiding the strip S in proper relationship to the cutting disks 42 is constructed as follows:

A pair of spaced standards 54 bolted to the bed plate 24 extend vertically upward and support between them, a horizontal shaft 56 on which an elongated guide block 58 is pivoted. The upper surface of said block has a longitudinal groove 60 which is slightly wider than the maximum width of the strip S and which lies symmetrical beneath the cutting disks 42, 42'. The entrance end of the groove may be flared out as at 62 (Figs. 3 and 4), to facilitate passage of the strip.

A narrow pilot strip 64, best shown in Fig. 6 holds the strip S in the groove 60. The bottom surface of the pilot strip is centrally cut away to form an elongated groove 66 intermediate the flanges 68. Said groove 66 is preferably slightly wider than the diamond-shaped link 22, and the thickness of the flanges 68 defining said groove is such that their outer walls will not quite be in rubbing engagement with the inside of the parallel rail portion 16. The inner corners of the flanges 68 may be rounded, as at 70, to conform to the fillet on the slider wing blank adjacent the base of the diamond-shaped link 22. In this manner, it will be seen that a close and accurate control is maintained over the position of the strip S as it passes beneath the cutting disks 42, 42'.

Suitable means, such as end plates 72, hold the guide strip 64 in position. Cover plates 74 are bolted to the guide block 58 to conceal the portions of the groove 60 left exposed by the pilot strip 64. Each of said cover plates 74 may be recessed at 76 where they overlie the groove 60

in order to provide sufficient room for passage of the strip S. The cover plates 74 may also be accurately cut away to form grooves 78 in which the cutting disks 42, 42' set. In the bottom of these grooves are apertures 80 to permit said cutting disks to project through the plates 74 and work on the strip S as it passes through the apparatus 10.

Plates 82 laterally overlie edge portions of the groove 60 rearwardly of the plates 74 so as to keep the strip S in said groove until the strip leaves the apparatus 10.

Means may also be provided to vertically adjust the position of the guide block 58 relative to the cutting disks 42, 42' and to thereby control the height of the trimmed rail portions 16 and 18. Such means comprises a pair of slots 84 disposed on each side of a threaded aperture 86, said apertures and slots being disposed remotely of the shaft 56.

A bolt 88 is threadedly received in the tapped aperture 84, and bolts 90 freely pass through the slots 86 and are threadedly received in tapped holes 92 in the bed plate 24. The bolts 90 have enlarged heads 94 adapted to abut against the upper surface of the guide block 58. The entire portion of the guide block where the bolts 88 and 90 are disposed may be cut away as at 95 (Fig. 4), so that the tops of said bolts will clear the bottom of the strip S being fed through the machine 10.

In order to vary the elevation of the strip S relative to the cutting disks 42, 42', it is merely necessary to loosen the bolts 90, adjust the bolt 88 until the desired elevation of the strip S is obtained, and then tighten the bolts 90 until their heads lock against the block 58.

In accordance with our invention, suitable means F is also provided to feed the strip S through the rail trimming machine 10. Said feed means is actuated from the common source of power P by a pulley 96, mounted on the shaft 32, and which through a chain 98 drives a pulley 100 fixed to the power input shaft 101 of a gear reduction box 102 carried on top of the journal box 40.

The power output shaft 104 of said gear reduction box has secured thereon a variable eccentric 106 on which the strap end 108 of an oscillating rod 110 is rotatably mounted. The throw of said eccentric may be adjusted by a regulator 105, and rod 110 may be adjusted by means of a central turnbuckle bolt 112. Lock nuts 114 fix said bolt after adjustment thereof. The driving end 115 of the link 110 is forked and straddles an end of a crank rod 116 mounted for rotation with a shaft 118 journaled between the upper ends of the standards 54 and disposed perpendicular to the groove 60. The forked driving end 115 of the link 110 and the outer end of the crank rod 116 are pivotally connected by a pin 120. Also mounted for rotation with the shaft 118 is a pendent, driven crank rod 122 on whose lower end a feed dog 124 is pivotally attached by a pin 125. The disposition of the feed dog 124 is such that its free end will rest on the cover plates 82. Said feed dog is biased to this position by a spring 126 fixed at one end to a stationary plate 124, and attached at the other end to a pin 130 extending from said dog. A hardened steel feed pin 132 at the extremity of the feed dog 124 has a pendent feed finger 134 thin enough to freely pass between the opposed edges of the cover plates 82 overlying the groove 60. The corner 136 of said feed

finger facing the cutting disks 42, 42' is chamfered.

It will be seen that the oscillating motion imparted to the rod 110 by the eccentric 106 is transmitted by the crank 116 and shaft 118 to the driving crank 122 which carries the feed dog 124. Thus, the feed finger 134 will be moved back and forth along the length of the strip S and will be guided in its movement by the plates 82. The throw of the eccentric is so adjusted that the movement of the feed dog is at least equal to the distance between similar points on consecutive diamond-shaped links 22 and preferably is equal to a whole multiple of this distance. During a feeding stroke the spring 126 keeps the forward face of the feed finger 134 in engagement with the rear vertical wall R of the diamond-shaped link 22. During retrograde movement of the feed finger said spring allows the feed dog 124 to be oscillated upwardly when the chamfered corner 136 rides over a diamond-shaped link. The position of the feed finger 134 may be controlled by adjusting the length of the turnbuckle bolt 112, and this adjustment may be so performed as to place the driving crank 122 in substantially vertical position at the middle of its stroke whereby the feed dog 124 will be substantially, linearly reciprocated.

The direction of feed is such that the strip is pulled beneath the cutting disks 42, 42' in such manner as to oppose rotation of said disks.

Due to the tendency of the feed finger 134 to reverse the direction of feed when traveling on a retrograde stroke, we find it desirable to provide a check dog comprising a lever 138 pivotally mounted on a shaft 140 extending between the standards 54. Said lever is rotatably biased in a clockwise direction (as viewed in Fig. 2) by a spring 142. An abutment screw 144 threaded in a stationary plate 146 limits the movement of said check lever under the influence of the spring 142. The operative end of the check lever 138, when the upper end of said lever is abutted against the screw 144 is so positioned that it will lie immediately behind the rear vertical wall R of a diamond-shaped link 22 at the end of a forward feeding stroke of the feed finger 134. During the feeding stroke a diamond-shaped link 22, as it passes under the operative end of the check lever 138, engages the chamfered surface 148 thereof and moves said lever out of the way. As soon as said diamond-shaped projection has moved past the check lever, said lever will spring back to its static checking position under the influence of the biasing spring 142, and by abutting a wall R, will prevent the strip S from moving backwards. Abutment screw 144 which controls the static position of the lever 138 can be adjusted to space the lower end of the lever 138 and feed finger 134 a distance apart equal to a whole multiple of the space between corresponding points on two adjacent diamond-shaped links 22. This space, it will be noted varies in strips of different size slider wing blanks making this adjustment desirable. A lock nut 150 is employed to fix the screw 144 in any adjusted position.

It will thus be seen that there is provided a method and means by which the several objects of this invention are achieved, and which is well adapted to meet the conditions of practical use.

As various possible embodiments might be made of the above invention, and as various changes might be made in the embodiment above set forth, it is to be understood that all matter herein set

forth or shown in the accompanying drawings is to be interpreted as illustrative and not in a limiting sense.

Having thus described our invention, we claim as new and desire to secure by Letters Patent:

1. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, guiding means to direct said strip under said material removing members transversely of said stationary axis and with each set of rails along a longitudinal axis of said strip operatively contacting one of said material removing members, said guiding means comprising a support for said strip and two spaced pairs of parallel walls running transversely of said stationary axis, each pair being spaced apart to slidably receive said rails on one longitudinal edge of said strip, said disks and guiding means being so constructed and relatively arranged that each of said disks will trim the full width of the rail with which it is in operative contact, and a common means for revolving said material removing members and actuating said feeding means.

2. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, guiding means to direct said strip under said material removing members transversely of said stationary axis and with each set of rails along a longitudinal axis of said strip operatively contacting one of said material removing members, said guiding means comprising a support for said strip, two spaced pairs of parallel walls running transversely of said stationary axis, each pair being spaced apart to slidably receive rails on one longitudinal edge of said strip and a wall lying between said support and said stationary axis and adapted to slidably receive the portion of said strip between said rails, said disks and guiding means being so constructed and relatively arranged that each of said disks will trim the full width of the rail with which it is in operative contact, and a common means for revolving said material removing members and actuating said feeding means.

3. An apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, and wherein projections of similar size and location are axially disposed between pairs of wing blanks along said strip, the combination of a pair of disk-like material removing members revolvable about a single stationary axis, means to feed said strip, guiding means to direct said strip under said material removing members transversely of said stationary axis and with each set of rails along a longitudinal axis of said strip operatively con-

tacting one of said material removing members, said guiding means comprising a guiding member having a groove therein slightly wider than the extreme width of said strip, said groove being disposed transversely of said stationary axis and a second guiding member overlying said first guiding member and having a groove therein parallel to and facing said first named groove, said second named groove being slightly wider than the maximum width of said projections, the width of said second guiding member being slightly less than the space between said rails and the bottom of said second guiding member being spaced from the bottom of said first named groove a distance slightly greater than the thickness of said strip, said material removing members and guiding means being so constructed and relatively arranged that each of said material removing members will trim the full width of the rail with which it is in operative contact, and a common means for revolving said material removing members and actuating said feeding means.

4. In an apparatus for reducing the height of oversized rails on a long strip of integrally connected slider wing blanks having uniformly spaced and disposed projections along the length thereof, the combination of a revolving material removing member, reciprocating means for feeding said strip by engaging said projections, check means for preventing retrograde movement of said strip during the non-feeding stroke of said reciprocating feeding means by engaging said projections, means to adjust the relative position of said feeding means and said check means so that the distance between said feeding means at the end of a feeding stroke and said check means will be equal to a whole multiple of the space between the projections on said strip, and guiding means to direct said strip under and with the rails operatively contacting said revolving material removing member.

5. In a method of reducing the height of oversized rails on a long strip of integrally connected wing blanks of sliders for slide fasteners wherein the rails associated with each of said wing blanks comprise portions parallel to the longitudinal axis and disposed along opposite longitudinal edges of said strip and contiguous outwardly diverging portions, the steps of revolving about a single stationary axis a pair of parallel milling cutters whose cutting faces are spaced apart a distance not greater than that between opposite parallel rail portions and extend beyond the outermost ends of the diverging rail portions, closely and accurately positively positioning said rails relative to said cutters by guiding said strip under a stationary member between said cutters and adjacent the periphery thereof and over another stationary member beneath and spaced from said first stationary member a distance slightly greater than the thickness of said strip, continuously feeding said strip to said cutters, and restricting said strip against movement parallel to the axis of revolution of said cutters at the point the latter is guided between said members.

6. In a method of reducing the height of oversized rails on a long strip of integrally connected wing blanks of sliders for slide fasteners wherein the rails associated with each of said wing blanks comprise portions parallel to the longitudinal axis of said strip and disposed along opposite longitudinal edges thereof and contiguous outwardly diverging portions, the steps of revolving a pair of spaced parallel milling cutters

about a single stationary axis, continuously longitudinally feeding said strip to said cutters, and closely and accurately positioning said rails relative to said cutters by passing said strip through a stationary guide at the point where said cutters operate on said rails to positively restrict movement of said strip in a plane including said axis at such point.

7. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, and guiding means to direct said strip under said material removing members transversely of said stationary axis and with each set of rails along a longitudinal axis of said strip operatively contacting one of said material removing members, said guiding means slidably engaging a portion of the surface of said strips facing said material removing members and comprising a stationary pilot member disposed between said material removing members adjacent the periphery thereof, said disks and guiding means being so constructed and relatively arranged that each of said disks will trim the full width of the rail with which it is in operative contact.

8. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, and guiding means to direct said strip under said material removing members transversely of said stationary axis and with each set of rails along a longitudinal axis of said strip operatively contacting one of said material removing members, said guiding means slidably engaging a portion of the surface of said strip facing said material removing members and comprising a stationary pilot member disposed between said material removing members adjacent the periphery thereof and a second member disposed beyond said cutters and spaced from said first stationary member along a line intersecting said axis a distance such that said strip is adapted to be slidably received between said guiding members, said disks and guiding means being so constructed and relatively arranged that each of said disks will trim the full width of the rail with which it is in operative contact.

9. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, and guiding means to direct said strip under said material removing members transversely of said stationary axis and with each set of rails along a longitudinal axis of said strip operatively contacting one of said

material removing members, said guiding means slidably engaging a portion of the surface of said strip facing said material removing members and comprising a stationary pilot member disposed between said material removing members adjacent the periphery thereof and a member immediately adjacent said pilot member to maintain said strip in sliding contact with said pilot member, said disks and guiding means being so constructed and relatively arranged that each of said disks will trim the full width of the rail with which it is in operative contact.

10. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, and guiding means to direct said strip under said material removing members transversely of said stationary axis and with each set of rails along a longitudinal axis of said strip operatively contacting one of said material removing members, said guiding means slidably engaging a portion of the surface of said strip facing said material removing members and comprising a stationary pilot member disposed between said material removing members adjacent the periphery thereof, the outer surface of said member being shaped to negatively match the end elevation of that portion of said strip between said rails, said disks and guiding means being so constructed and relatively arranged that each of said disks will trim the full width of the rail with which it is in operative contact.

11. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, and guiding means to direct said strip under said material removing members transversely of said stationary axis and with each set of rails along a longitudinal axis of said strip operatively contacting one of said material removing members, said guiding means slidably engaging a portion of the surface of said strip facing said material removing members and comprising a stationary pilot member disposed be-

tween said material removing members adjacent the periphery thereof, the outer surface of said member being shaped to negatively match the end elevation of that portion of said strip between said rails, and a member immediately adjacent said pilot member to maintain said strip in sliding contact with said pilot member, said disks and guiding means being so constructed and relatively arranged that each of said disks will trim the full width of the rail with which it is in operative contact.

12. In an apparatus for reducing the height of oversized rails on a long strip of integrally connected slider wing blanks wherein the rails are disposed along opposite longitudinal edges of said strip and include portions parallel to the longitudinal axis of said strip and contiguous portions diverging outwardly therefrom, the combination of a pair of disk-like material removing members revolvable about a single stationary axis, means to feed said strip, and guiding means to direct said strip under said material removing members transversely of said stationary axis and with each set of rails along a longitudinal axis of said strip operatively contacting one of said material removing members, said guiding means slidably engaging a portion of the surface of said strip facing said material removing members and comprising a stationary pilot member disposed between said material removing members adjacent the periphery thereof and a pair of elements spaced parallel to and extending transversely of said axis for restricting movement of said strip parallel to said axis, said disks and guiding means being so constructed and relatively arranged that each of said disks will trim the full width of the rail with which it is in operative contact.

13. In an apparatus for reducing the height of oversized rails on a long strip of integrally connected wing blanks of sliders for slide fasteners, the combination of a pair of disk-like material removing members mounted to turn about a single stationary axis, means to revolve said members, a stationary guide member at the point where the material removing members operate on said rails, said guide member being constructed and arranged to slidably pass said strip in a direction transverse to said axis with each of said rails operatively contacting one of said material removing members and to positively restrict movement of said strip in a plane including said axis and such point, and means to move said strip through said guide member.
